DOOR STOP

Burt M. Hurlbut, Pueblo, Colo., assignor to San
Isabel Novelty Works Company, Pueblo, Colo.,
a corporation of Colorado

Application February 12, 1935, Serial No. 6,204

3 Claims. (Cl. 292—196)

This invention relates to an improved door stop and seeks, among other objects, to provide a device of this character which may be readily attached to a door and which will effectually retain the door in a desired open position.

Another object of the invention is to provide a door stop embodying a bolt which is engageable in a socket for retaining the door in a closed position.

10 A further object of the invention is to provide a door stop which may be operated easily and which will be positive in action.

15 And a still further object of the invention is to provide a device of this character which may be manufactured to market at a reasonable price.

Other and incidental objects of the invention not specifically mentioned will render themselves apparent as the description of the invention proceeds.

20 In the sheets of drawings forming a part of my application:

Figure 1 is a plan view, partly in section, and showing a pair of the devices as they would appear mounted on a pair of garage doors with the doors in closed position and the bolts locked in their respective sockets.

Figure 2 is an enlarged vertical sectional view on the line 2—2 of Figure 1.

Figure 3 is a fragmentary vertical sectional view taken on the line 3—3 of Figure 2, and looking in the direction indicated by the arrows.

Figure 4 is an enlarged fragmentary detail plan view showing the door stop as it would appear in operative position, with the bolt shown 35 in raised position.

Figure 5 is a fragmentary detail horizontal sectional view taken on the line 5—5 of Figure 4.

Figure 6 is a side elevation showing a slightly modified form of my invention.

40 Figure 7 is a front elevation of the device as shown in Figure 6, with the stop bar employed in inoperative position.

Figure 8 is a side elevation showing a still further modified form of the invention.

45 Figure 9 is an enlarged fragmentary detail sectional view showing the ends of the connecting links shiftably mounted in the sleeves employed.

Figure 10 is a vertical sectional view of a still further modification, said view showing the stop 50 bar employed in operative position.

Figure 11 is a side elevation of the modification shown in Figure 10 and showing the stop bar in inoperative position.

Figure 12 is a front elevation of said modified 55 form of the invention.

Referring now more particularly to the drawings, wherein like numerals of reference designate like parts throughout the several views, in the preferred embodiment of the invention the numeral 1 indicates a door which is mounted in a frame 2. The door may be either of the single type or it may comprise one of two doors, as shown in Figure 1. The door is mounted over a preferably concrete floor 3 in which is embedded a latch plate 4 having a socket 5 therein. 10

Mounted on the door 1 near the swinging rail thereof and on the lower portion of said rail, is a frame or body 6 which is preferably formed of channel iron and is U-shape in cross section. The frame is secured to the door by means including brackets 7 so that it will be rigidly mounted thereon at all times. 15 Swingly mounted on the frame at its upper end portion is an actuating lever 8 which is U-shape in cross section and straddles the upper end of the frame 6. The lever 8 is formed with side walls 9 which taper in width to a point substantially midway of the length thereof, as better seen in Figure 2 of the drawings. The walls 9 are of uniform width throughout the remainder of their length. Formed in the frame or body 6, near the upper 20 end thereof, are oppositely disposed longitudinally arranged rectangular slots 10. The lever 8 is secured in position on the frame by means of a pin 11 which extends through the frame and through said lever. Formed in the body 6, near its lower end, are oppositely presented longitudinally arranged rectangular slots 12, the purpose 25 of which will be described hereinafter.

Snugly but slidably mounted within the body 6 and extending throughout the major portion of its length is a preferably channel iron actuating member 13. As better seen in Figure 3 of the drawings, the actuating member 13 is provided near its lower end with a bolt 14. The bolt 14 30 is formed with a plurality of openings 15 and said bolt is secured to the member 13 by means of pins 16 extending through certain of said openings 15. It should be understood that the height of the bolt 14 may be varied by setting said bolt 35 at a desired height within said member 13 and projecting the pins 16 through the proper registering openings 15. The height of this bolt will, of course, be determined by the actual operating conditions. 40

Shiftably connecting the lever 8 with the actuating member 13 is a link 17 which comprises side rods 18 and a connecting rod 19, which connecting rod projects through the slot 10 and through the upper end portion of the actuating member 50 55

13. As shown in Figure 3, the connecting rod is in the form of a bolt with a locking nut 29 thereon. The corresponding opposite ends of the side rods are connected to substantially the mid-portions of the walls 9 and in off center relation to the pin 11 by means of studs 21. Riveted or otherwise secured to the actuating member 13 within the slot 10, is a hook 22 having a depending bill 23 thereon. Said bill is adapted to engage in an opening 24 formed in a keeper plate 25 which is carried on the actuating member of an adjacent door stop, as seen in Figure 1, for retaining a pair of the devices in locked position when used on a double door, and thus provide supplemental locking means.

Swingingly connected to the frame 6, near its lower end and adjacent its forward wall, is a stop bar 26 which is substantially U-shape in cross section and is formed preferably from heavy sheet metal. As better seen in Figures 4 and 5 of the drawings, the bar is provided with side walls 27 and a bottom wall 28 which is cut away near its inner end to accommodate the frame 6 and permit ready swinging movement of the bar. The stop bar is connected to the frame by means of a pin 29 and carried in the free earth-engaging end of the bar is a foot 30 which is reduced near its inner end to fit snugly in the lower end of the bar 26, rivets 31 retaining the foot in position on the bar.

Swingingly connecting the stop bar 26 with the actuating member 13 is a link 32 which is of similar construction to the link 17 and comprises side arms 33 and a connecting rod 34 which extends through the slot 12 in the frame and is firmly secured to the actuating member.

The operation of the device is as follows:

The device, as shown in Figure 1, is in locked position with the bolt engaging in the socket 5. When it is desired to free the bolt from the socket and open the door, the lever 8 is raised upwardly and outwardly for raising the actuating member 13 within the frame 6 and, at the same time, freeing the bolt 14 from the socket 5. The door may then be opened to the desired position. As the bolt is being lifted from the socket 5, the stop bar 26 will be swung downwardly and after the door has been opened the lever 8 is shifted upwardly to its limit for shifting the bar 26 downwardly so that the foot 30 will be engaged with the surface beneath the bottom edge of the door. The stop bar will then retain the door in the desired opened position.

When it is desired to close the door, it is only necessary to shift the lever 8 partially downwardly so as to free the foot 30 from the surface therebeneath. The door may then be closed. After the door has been closed to a position wherein the bolt 14 overhangs the socket 5, the lever 8 is shifted downwardly to its limit. The bolt 14 will, by this shifting movement, be engaged in the socket 5 and the stop bar 26 will be shifted to its inoperative position, as shown in Figure 2 of the drawings. The device, as will be readily understood, may be operated with the utmost facility and may be installed with ease.

Referring now more particularly to the modification of the invention illustrated in Figures 6 and 7 of the drawings, the numeral 35 indicates the frame of a door on which is mounted a body 36, formed preferably of wood. The body is supported on the door frame by means of brackets 37 and swingingly connected to the body 36 between said body and the door frame, and between said brackets 37, is an actuating member 38 provided

at its lower end with a bolt 39 which is secured to the actuating member by means of rivets 40. It should be understood that the bolt may be adjusted to various heights on the actuating member, as determined by use. Swingingly connected to the actuating member 38, at its upper end, is a handle or lever 41 which is connected to said actuating member by a hinge 42. Said handle is also connected to the body 36 by means of a preferably heavy wire link 43, the bight portions of which are journaled in preferably metal sleeves 44 which are embedded in the handle and body. Swingingly connected to the lower end portion of the actuating member 38 is a stop bar 45 which is preferably formed of wood and is provided with a metal toe plate 46. The stop bar is connected with the actuating member by means of a hinge 47 and is also pivotally connected to the body by means of a link 48. As best seen in Figure 6 of the drawings, the lower end portion of the body 36 is tapered in thickness, as shown at 49, and the body portion of the stop bar is also tapered in thickness so that said bar may lie, when in inoperative position, near the face of the body 36 throughout the major portion of its length. The stop bar will thus be kept out of the way when not in use.

The device, as shown in full lines in Figure 6 of the drawings, is in locked position with the bolt 39 disposed in a socket 50 which is sunk into the surface beneath the door. The door is thus locked in position. When it is desired to open the door, the handle 41 is swung outwardly and downwardly, as shown in dotted lines in Figure 6, for rocking the actuating member inwardly and upwardly and, at the same time, shifting the stop bar outwardly and downwardly, as shown in dotted lines. The handle may be shifted only partially while the door is being swung so that the bolt 39 will be freed from the socket and the stop bar 40 will be out of engagement with the surface beneath the door. When the door has been swung to the desired open position, the handle may be swung to its downward limit for engaging the toe plate 46 in the surface beneath the door and thus retain the door in open position.

Mounted on the actuating member 38 on one side wall thereof, substantially medially of its length, is a hook 51 having a bill 52 adapted to engage in an opening formed in a keeper plate 53 which is secured to the actuating member of an adjacent door stop of identical construction with the one just described. It will be understood that the general idea of the modification is identical with that of the preferred form.

Referring now to the modification of the invention as shown in Figure 8 of the drawings, the numeral 54 indicates the frame of a door on which is mounted a body 55 which is formed of wood or other suitable material. An actuating member 56 is associated with the body 55 and is adapted to be positioned in superposed relation to said body 55. A link 57, which is preferably formed from heavy wire, has one end portion swingingly connected to the body 55. As better shown in Figure 9 of the drawings, the bight portions of the link are secured in sleeves 58, in the body 55, which are preferably formed of metal, so that swinging of the link will not cause the relatively soft wood to wear away. A handle 59 is connected to the actuating member 56 by means of a hinge 60. The opposite end portion of the link 57 is swingingly connected to the handle 59 so that, as will be seen, the link 57 swingingly connects the body 55, through the

handle 59, to the actuating member 56 which is, as stated, swingingly connected to said handle 59. The handle is shiftable outwardly and upwardly for lowering the actuating member along the surface of the body 55. A stop bar 61 is connected to the body 55 by means of a hinge 62 and said stop bar is connected to the actuating member by means of a link 63. As seen in dotted lines in Figure 8, when the handle 59 is swung upwardly, the actuating member 56 is permitted to slide downwardly and the stop bar is permitted to swing outwardly and downwardly into engagement with the surface beneath the door. The door will thus be retained in a desired locked position. This modification of the invention is identical with that of the preferred embodiment and other described modification to the extent that the locking bar is employed. No locking bolt is shown in this form of the invention.

Referring now more particularly to the modification of the invention as shown in Figures 10, 11 and 12, the numeral 65 indicates a preferably wood body or frame which is secured to a wall 66 by means of screws 67. Slidably mounted on the body 65 is a preferably wood actuating member 68 which is held in overlying relation to the frame or body by means of guide loops 69. A latch 70 is carried on the actuating member 68 and is adapted to engage a keeper plate located adjacent the door for that purpose. Mounted on the body 65 near its upper end are guide plates 71 which are formed preferably from sheet metal and extend outwardly in parallel spaced relation at each side of the body. The guide plates may be of any desired shape but, in the present instance said plates are formed with an arcuate bottom edge and straight top and rear edges 73 and 74. Formed in the guide plates 71 are oppositely disposed guide slots 75, the corresponding bottom edges of each of said guide slots being formed with a recess 76. As best seen in Figure 12 of the drawings, the lower end portion of the actuating member is cut away medially of its width to receive a bolt 77 which is adjustably held in position in the actuating member by means of pins 78. Associated with the actuating member 68, at its upper end, is a handle 79 which may be formed of wood and which is connected to said actuating member by means of a hinge 80. The upper end portion of the handle is normally disposed between the guide plates 71 and guide screws or bolts 81 are passed through the slots 75 and into the handle so that said handle will, in its swinging movement, be shifted outwardly to follow said guide slots 75. Mounted on the lower end portion of the body 65 is a pair of guide plates 82 which are of similar construction to the guide plates 71 but differ in the respect that guide slots 83 are provided and said guide slots are relatively short and are disposed in parallel spaced relation to the substantially straight bottom edges 84 of said plates. The plates are provided with arcuate edges 85. Associated with the actuating member 68 at its lower end, is a stop bar 86, preferably formed of wood, which is provided with a metal end 87 and is swingingly connected to the actuating member 68 by means of a hinge 88. The inner end portion of the stop bar is adapted to swing between the guide plates 85 and said stop bar is provided at each side with guide bolts 89 adapted to slide in the guide slots 83. As better seen in Figure 12 of the drawings, the stop bar is provided at its inner edge, adjacent the hinge, with a medial cut away portion

90. This cut away portion is adapted to receive the lower end portion of the bolt 77 when said stop bar is in operative position so that the stop bar will be permitted to swing downwardly to its fullest extent.

In operation, it will be seen, by referring to Figure 11 of the drawings, that when the device is in operative position, the lever 79 will be permitted to assume a position in a vertical plane with the actuating member 68 and by virtue of the fact that the guide plates 82, with the guide slots 83, are employed, the stop bar will be permitted to lie in a substantially vertical plane against the actuating member 68, the lower end portion of said stop bar being shifted outwardly with the guide bolts 89 riding in the slots 83. By this arrangement, the device, when in inoperative position, will take up but a small amount of space and the stop bar will not get in the way when the door is being swung. As best seen in Figure 11, the bolt 77 will be seated in an appropriate socket, as in the other forms of the invention, when the device is in inoperative position.

When it is desired to shift the stop bar to operative position, the lever 79 is swung outwardly and downwardly, the guide bolts 81 riding in the guide slots 75 of the guide plates 71. As the lever is swung outwardly to the extremities of the slots 75, the actuating member 68 will be 25 permitted to rock slightly upwardly between the guide plates and, at the same time, the stop bar will be swung outwardly and downwardly, its swinging movement being taken care of by the riding of the guide bolts 89 in the guide slots 83. 35 When the lever has reached its lowermost position, substantially parallel to the actuating member, the stop bar will be disposed at its lowermost position with the guide bolts 89 abutting the inner extremities of the slots 83. As best 40 seen in Figure 11 of the drawings, the recess 76 is formed along the longitudinal edge of the guide slots 75 substantially medially of the lower boundaries thereof and, when the lever 79 is in its lowermost position, the guide bolts will be seated in these recesses formed in the plates. These recesses permit the lever to lie in substantially parallel relation with the actuating member when the device is in operative position. Aside from the refinements embodied in the employment of the guide plates and guide bolts, this modification of the invention is essentially the same as that of the preferred form and the other modifications.

Attention is directed to the fact that I have 55 provided in the preferred form of the invention and in the modifications, a device simple in construction and positive in operation, which may be manufactured in quantity to retail at an attractive figure.

Having thus described the invention in the specification, what I claim as new is:

1. A door stop including a body adapted to be secured to a surface, an actuating member associated with the body, a handle connected with the actuating member, a link connecting the handle to the body, said link having bight portions, sleeves carried by the body and handle and journaling the bight portions, a stop bar swingingly connected with the body at the end remote 70 from the handle connection, a link connecting the stop bar with the actuating member, and a toe plate carried by the stop bar, said handle being shiftable upwardly for permitting outward swinging movement of the stop bar with conse- 75

quent engagement of the toe plate thereof with a surface beneath the first mentioned surface whereby said first mentioned surface will be prevented from shifting, said handle and stop bar 5 being shiftable toward and away from each other in stop bar retracting and engaging directions respectively.

2. A door stop including a body, an actuating member associated with the body and adapted 10 to swing outwardly therefrom, a handle associated with the actuating member, a hinge swingingly connecting the handle with the actuating member, a link swingingly connecting the handle and one end of said body, a stop bar, a hinge 15 swingingly connecting the stop bar with the body, and a link swingingly connecting the actuating member with the stop bar, said handle being shiftable for moving one end of the actuating member away from the body and shifting the 20 stop bar into engagement with a surface for hold-

ing a door, said handle and stop bar being shiftable toward and away from each other in stop bar retracting and engaging directions respectively.

3. In a door stop, a body, an actuating member associated therewith and adapted to swing away from said body, a handle swingingly connected with the actuating member, means swingingly connecting the handle actuating member with the body, a stop bar swingingly connected with the body, and means swingingly connecting the stop bar with the actuating member, said handle being movable for shifting one end of the actuating member and swinging the stop bar into locking position for holding a door against movement, said handle and stop bar being shiftable toward and away from each other in stop bar retracting and engaging directions respectively whereby space will be conserved. 5 10 15

BURT M. HURLBUT. 20
